UNITED STATES PATENT OFFICE.

FRANK PROX, OF TERRE HAUTE, INDIANA.

SECTIONAL STEAM-BOILER.

SPECIFICATION forming part of Letters Patent No. 365,759, dated June 28, 1887.

Application filed April 25, 1887. Serial No. 236,007. (No model.)

To all whom it may concern:

Be it known that I, FRANK PROX, a citizen of the United States, residing at Terre Haute, in the county of Vigo and State of Indiana, 5 have invented a new and useful Improvement in Sectional Steam-Boilers, of which the following is a specification.

My invention relates to an improvement in that class of steam-boilers which consists of a 10 series of like or similar sections secured together to form a common water and steam receptacle.

The objects of my improvement are, first, to provide a boiler-section which may be easily 15 cast in one piece, and which shall present a large heating-surface, and, second, to so group a series of such sections as to form a grate-support and flues which will insure the thorough circulation and utilization of the fire and 20 heated gases, all as hereinafter fully described.

The accompanying drawings illustrate my invention.

Figure 1 represents a side elevation of one of the boiler-sections. Fig. 2 represents a section through *a*, Fig. 1. Fig. 3 represents a section through *b*, Fig. 2. Fig. 4 represents a central vertical section of the entire boiler. Fig. 5 represents a rear elevation of the boiler. Fig. 6 represents a central horizontal section 30 of the entire boiler. Figs. 7 and 8 represent an elevation and a plan of a modified form of my boiler.

Each section consists, substantially, of a pair of tubular elliptical rings, *A* and *B*, arranged 35 one within the other, having a space between them and connected by short tubular bars *c c* and *d d*. Two of the sections in each boiler are provided with a cross-bar, *e*. (Shown in dotted lines in Fig. 1 and in section in Fig. 4.) 40 Said bar *e* is arranged near the lower end of ring *B*, and is for the purpose of forming a support for the grate-bars *f*. Each section is cast in one piece, and is provided with openings *h h* and *i i*. Around each of the openings *h* and *i* is formed on one side of the section a projection, *j*, and on the opposite side is a depression, *k*, so that when a series of sections are laid together the projections of one section fit into the depressions of the next 45 section.

In setting up a boiler I take first a section (marked 1 in Figs. 4 and 6) like that illus-

trated in Fig. 1, except that it is provided with a cross-bar, *e*, as before described. This is set on edge. Next to this I place two sections 55 (marked 2) made without the short tubular bars *c c*. Then follows a series of sections like Fig. 1, (marked 3,) proportioned in number to the capacity of boiler required and the length of the grate-bars. In the boiler shown said sections are three in number. Next comes another section 1, having the grate-bar support *e*; then two or more sections 2, and at last a section (marked 4) formed without the lower half of ring *B*. As the several sections are 60 put together a suitable packing is put into the depressions *k* in each section, thus forming a steam-tight joint around the openings *h* and *i*. Through these openings communication is established between the several sections. The 65 several sections are clamped together by bolts *l l* and *m m*, passing through the openings *h* and *i*. Said bolts are of considerably less diameter than the openings, so as to leave a space 70 all around the bolts. A plate, *O*, covers all 75 of the first section except a central opening, *p*, opposite the grate, and the rear section is covered, except the upper half of the space between rings *A* and *B*, by a plate, *R*. A plate, *s*, inserted between two of the sections, 80 serves to shut off the space below the grate from the rest of the rear end of the fire-space, and, rising above the grate-bars, answers the purpose of a "bridge-wall" to direct the flames 85 to the upper part of the fire-space. It will be observed that when the boiler is complete the space between the rings *A* and *B* is divided 90 by the bars *c c* and *d d* into four flues, *t t* and *u u*. The flues *t t* communicate with the flues *u u* only through the space in the sections 2 2, 90 where there are no bars *c*, and the flues *u u* communicate with the fire-space inside the rings *B* only through the space formed by leaving out the lower half of ring *B* in the last section, 4. The upper portions of several of the sections are connected by a steam-pipe, *T*.

In operation the interiors of rings *B* form the fire-space, from which the fire and smoke pass backward and downward to the rear end 100 of flues *u*; thence forward along said flues to the openings *x x*, Fig. 6, through which they pass to flues *t t*, and backward along said flues to the chimney at the rear of the boiler. In

the modified form shown in Figs. 7 and 8 the sections are laid horizontally one above the other on a base, *Ba*, which carries the grate-bars, and two or more of the sections have a portion of both rings cut away, and are joined by hollow bars *br*, which form a fuel-feed-door-frame, which, on account of the constant circulation of water about it, cannot be warped or burned out.

10 I claim as my invention—

1. A boiler-section consisting of two tubular rings arranged one within the other, having a space between the rings, short tubular bars extending across said space and connecting said rings, and a tubular bar extending across the inner ring and adapted to form a grate-bar support, said rings and bars being all cast in a single piece, substantially as specified.

15

2. A boiler-section consisting of two tubular incomplete rings arranged one within the other, having a space between the incomplete rings, said rings being connected at their ends by tubular bars, all being cast in a single piece, substantially as specified.

20
25
3. The boiler consisting of the several sections 1, 2, 3, and 4, arranged as shown and described, the bolts passing through said sections and clamping them together, the grate arranged within the series of sections, and the plates closing the end sections, all combined and arranged to co-operate substantially as and for the purpose specified.

FRANK PROX.
